[57]

CLAIM

The ornamental design for a frame for a cart, as shown and described.

DESCRIPTION

FIG. 1 is a top right front perspective view of a frame for a cart showing our new design. The broken lines are for illustrative purposes only and form no part of the claimed design.

FIG. 2 is a right side elevational view thereof; the left side elevational view being a mirror image;

FIG. 3 is a rear elevational view thereof;

FIG. 4 is a front elevational view thereof;

FIG. 5 is a top plan view thereof; and,

FIG. 6 is a bottom plan view thereof.
